J. M. ALLEN

METHOD OF MAKING HOSIERY

Filed Dec. 22, 1923

UNITED STATES PATENT OFFICE.

JOHN M. ALLEN, OF TORONTO, ONTARIO, CANADA.

METHOD OF MAKING HOSIERY.

Application filed December 22, 1923. Serial No. 682,206.

The principal objects of the invention are, to produce a full fashioned hose free from seams or welts on the underside of the foot and in the heel and having smoothly tapering ankle and leg portions and to improve on the method of manufacture described in my co-pending application, Serial Number 665,909, filed October 1st, 1923.

A further object is to devise a practical method of knitting a full fashioned hose upon a circular knitting machine.

The principal features of the invention consist in forming a triangular-shaped heel and forming the foot section in two portions 15 seamed together at the sides, the angle portion being shaped to match the triangular heel and being connected thereto, the ankle and leg portion being gradually increased in diameter by increasing the number of 20 stitches gradually.

The method of knitting consists in first forming a supporting circular fabric and knitting thereto a triangular-shaped fabric to form a heel by reducing the number of 25 needles in operation to the minimum and gradually increasing the number of needles in operation to form a fabric, of increasing width until the maximum width of the heel is produced, then forming the heel gore and 30 continuing the operation of knitting with a portion of the needles to form the bottom half of the foot, then forming a toe gore and producing the fabric for the upper half of 35 the foot by the use of a portion of the needles, then forming the ankle portion by increasing the number of needles and knitting into the supporting circular fabric a number of stitches equal to the taper of the heel section, then continuing the knitting of 40 the leg portion with a gradually increasing number of needles to form a tapering structure, then looping the supporting fabric along the tapered edges of the heel and the tapered edges of the ankle portion and severing 45 the surplus of the supporting fabric.

In the accompanying drawings, Figure 1 is an elevational view of the foot portion of a stocking constructed according to this invention.

Figure 2 is a diagrammatic view illustrating the steps of the method of knitting.

Figure 3 is a perspective view showing the manner of supporting the various sections of the hose in the knitting process.

Figure 4 is a perspective detail illustrating the manner of looping the heel.

Figure 5 is a diagrammatic view similar to Figure 4 on a reduced scale.

The manufacture of hosiery upon circular knitting machines has been restricted to the 60 cheaper grades, because of the inability to produce a full fashioned shape, that is, a shape of stocking in which the angle and foot portion has substantially the same 65 length of loop in the stitches as the leg portion, so that the hose will have uniform elasticity.

In the present process a full circle of a knitted fabric using the entire number of 70 needles is first knitted. This is represented by the band 1 illustrated in Figures 2 and 3.

The entire complement of needles with the exception of two or three are then held inoperative in a manner well known in the art and knitting is then continued, bringing into 75 operation extra needles at the ends of the rows as may be desired, so as to produce a V-shaped fabric, as indicated by the numeral 2. This V-shaped fabric 2 in Figure 2 is not shown attached to the band but the joined 80 arrows in the angle are intended to indicate that the fabrics so joined are knitted together. This is of course necessary and the actual manner in which manufacture is carried out, in that this tapered fabric must be 85 knitted to the band 1 in order to accomplish the result which will hereinafter appear.

When the desired width of heel has been produced the needles are again manipulated 90 in the formation of the heel gore 3 according to the usual practice. The knitting is then continued with the desired number of needles to form the lower half section 4 of the foot and when the desired length of such section 95 has been knitted, the toe gore 5 is formed.

The knitting then continues forming the upper half section 6 of the foot portion and when the length of this section equals the length from the toe gore to the heel gore the 100 width of the fabric is increased by the gradual inclusion of needles upon which the stitches are retained, thus knitting this portion of the leg structure to the band.

This arrangement is clearly illustrated in 105 Figure 3, the band 1 being shown with the heel section 2 knitted thereto in a gradual increasing width until the full width is obtained at the points 2'.

The knitting of the heel gore 3 then progresses and after the foot portions 4 and 6 are formed the fabric is then knitted into 110

the loops of the band 1 at the points 2' and continued at either side of the band 1 for a length equal to the length of the fabric from the point 2' to the apex of the heel. The 5 leg fabric is then knitted for a desired length with a selvedge edge and as the diameter of the leg is desired to be increased in the shaping thereof further needles are put into action on each side until the full 10 complement of needles is in operation.

After the leg of the stocking is completed the connecting portion 9 of the band 1 is cut away and a row of stitches of the supporting fabric parallel with the heel portion 15 2 are cast on to the points of a looping machine in the manner illustrated in Figure 4. The fabric is then reversed from the points 2' on either side and the stitches of the supporting fabric 1 parallel with the portions 20 7 are cast back over the same points as that of the portion 2, until the two portions of the fabric meet. The looping machine then forms the loop stitch 10 which connects the 25 V heel to the ankle. This loop stitch introduced here not only connects the heel with the ankle portion in a very slight manner but does so without producing a seam or welt which would be uncomfortable to the wearer.

30 A stocking such as described may be proportioned so as to produce a perfectly fitting garment without puckers or welts and the only seams are at the sides extending between the heel and toe gores where they will 35 not be uncomfortable or injurious.

What I claim as my invention is:—

1. A method of knitting hosiery consisting in first knitting a circular fabric on a circular knitting machine, then withdrawing 40 the major portion of the needles from operation, then knitting the heel, foot and ankle portions with a reciprocating movement forming a tapered heel and correspondingly shaped ankle which tapered heel 45 and ankle portions are knitted into the first knitted circular fabric to form taper selvedge edges, then continuing the knitting beyond the last knit ankle portion to form the leg portion of the stocking, then looping 50 said taper edges together, removing the first knit circular fabric and seaming the remaining edges together to complete the formation of the stocking.

2. A method of knitting hosiery consisting in first knitting a circular fabric on a 55 circular knitting machine, then withdrawing the major portion of the needles from operation, then forming a diverging fabric by gradually increasing the number of needles in operation knitting same to the circular fabric first produced, then continuing the knitting operation to form the foot portion in bottom and top half sections, then knitting in the ankle portion by a gradual increase in the number of needles used connecting same to the original circular knit portion, then continuing the knitting beyond the last knit ankle portion, completing the knitting of the leg portion to the desired dimensions, then removing said circular knit portion and looping the stitches of the diverged heel portion to the stitches of the ankle portion adjoining the top foot section and then seaming the back of the leg portion and the sides of the foot portion. 75

3. A method of knitting hosiery consisting in first knitting a circular fabric on a circular knitting machine, then withdrawing the major portion of the needles from operation, then forming a divergent fabric 80 by gradually increasing the number of needles in operation knitting same to the circular fabric first produced, then continuing the knitting operation to form the foot portion in bottom and top half sections, then knitting in the ankle portion by a gradual increase in the number of needles used connecting same to the original circular knit portion, then continuing the knitting beyond the last knit ankle portion, completing the knitting of the leg portion to the desired dimensions, then removing said circular knit portion and casting a row of stitches of the supporting fabric adjacent to the edges of the diverging heel portion upon a 85 looping machine, then doubling back the ankle portion knitted to the circular section and casting the stitches of the supporting fabric on to the points from either side to bring the edges together at the apex of the convergent heel, then loop stitching these cast on loops together, then seaming the back of the stocking and the sides of the foot sections. 100

JOHN M. ALLEN.
